UNITED STATES PATENT OFFICE.

PETER WILLIAM HALLVARSON, OF CALGARY, ALBERTA, CANADA.

LINING DEVICE.

Application filed August 26, 1922. Serial No. 584,560.

My invention relates to a lining device, the object of which is to provide a device that will fill the interstices of the surface surrounding a bore hole or well with a plastic cementing material thereby preventing collapse of the walls of the bore hole.

These objects I accomplish with the device illustrated in the accompanying drawings in which:

10 Fig. 1 is a plan view of the cap to which the suspending cable is secured.

Fig. 2 is a sectional elevation through the entire device.

Fig. 3 is a horizontal cross section.

15 Fig. 4 is a vertical elevation.

Similar characters refer to similar parts throughout the several views.

A cylindrical container is formed of a perforated side member *a*, to one end of which a 20 base plate *b*, is secured, the other end being provided with a cap *c*. The cap and base are secured by set screws *d*, to the perforated side member *a*. Internally of the said side member *a*, is a collapsible lining *e*, which

25 prevents plastic material *f*, inside the container from passing through the perforations *g*, in the side member until extraordinary pressure is exerted from the inside of

the cylinder. Mounted centrally of the said container and extending from the cap to the 30 base, is an expanding member *h*, in the form of a mild explosive cartridge and provision is made through the cap *c*, for igniting the cartridge, an orifice *i*, being provided for this purpose.

35 The ignition of the cartridge causes expansion of the contents of the cylinder, which expansion breaks the collapsible lining *e*, and forces the plastic material *f*, through the orifices *g*.

40 What I claim is:

1. In an article of the class described a perforated cylindrical casing with cap and base members secured thereto, a collapsible lining within the said cylindrical casing, an 45 explosive core member mounted centrally of the said cylinder through the cap for actuating the expansion of the said core, a cementing material within the said casing around the said core adapted to be forced through 50 the perforations in the casing by the action of the explosive core.

2. The process of cementing a well, comprising lowering cement down a well and blasting the cement into the well formation.

PETER WILLIAM HALLVARSON.
